UNITED STATES PATENT OFFICE

JAMES S. LANG, OF BOSTON, MASSACHUSETTS; OLD COLONY TRUST COMPANY EXECUTOR OF SAID JAMES S. LANG, DECEASED

VIBRATORY MASSAGE APPARATUS

Application filed May 5, 1927. Serial No. 189,137.

The present invention belongs to that class of curative agencies in which the vibration of the parts is utilized to stimulate the flow of blood through the tissues, bringing about a more healthful condition thereof, or to relieve pain or nervous tension by the vibration of the proper areas.

The object of the invention is to enhance the value of tissue vibration, in an improved manner by the use of periodic or rhythmic variations in air pressures, either above or below the atmospheric normal. Another object is to provide an apparatus for repositioning displaced parts or tissue by air pressure and then subjecting them to vibration in their normal position so that they may remain in that position. Another object is to provide an apparatus for stimulating the flow of blood and the nourishment of the parts by the application of a rhythmic vacuum. Another object is to provide an improved means of mechanically vibrating the body tissues.

It is well known that a vacuum applied to the surface of the body will draw the blood to the parts. The application of a continuously applied vacuum will however distort the parts and by drawing the tissues together will to a certain extent hinder the movement of the blood in them. I therefore apply in the present invention an intermittent or rhythmic vacuum which allows the tissues to periodically separate thus facilitating the movement of the blood to the parts with a less degree of vacuum than would otherwise be required and consequently with less discomfort.

The invention can best be seen and understood by reference to the drawings in which—
40 Figure 1 is a side view partly in vertical section of the apparatus.

Fig. 2 is a section of an alternating detail.

Fig. 3 is a plan of the apparatus.

Fig. 4 is a front elevation, and

45 Figs. 5 to 9, inclusive, are a set of graphs illustrative of various vibratory effects obtainable by the apparatus, as will hereinafter be referred to.

50 Referring to the drawings:

11 represents an air container having an

air chamber or passage 12 within it. The container 11 functions also as a valve control panel as the various valve controls are mounted upon it. Leading from the container and lower end of the air passage 12 within it, is an outlet communication 13 consisting of a flexible tube the free end 14 of which is provided with any one of applicators suitable for use on various parts of the body which it is desired to treat. As shown in the drawings the tube is provided with an applicator 15 suitable for treatment of the ear drum.

The periodic or rhythmic air pressure fluctuations are obtained within the container and in its outlet communication by means of air-displacing mechanisms 16, 17 and 18, respectively, fixed to the combined air container and control panel 11. The air-displacing mechanisms 16, 17 and 18 are of similar construction, each mechanism consisting of a cup-shaped member 19 which is closed across its outer edge or rim by an elastic diaphragm 20, which is held in place by a clamping ring 21. The chambered interior of each of the members 19 beneath its diaphragm connects with the chambered interior or passage 12 of the air container, to which end the member 19 of the air-displacing mechanism 16 is provided in its base with a port 22 which registers with a port 23 in the air container, leading to the interior thereof. Likewise the air-displacing mechanism 17 is provided with a port 24 connecting with a port 25 in the air container, and the air-displacing mechanism 18 with a port 26 which registers with a port 27 in the air container.

The several diaphragms are actuated in the following manner: To the centres of the diaphragms are fastened the ends of connecting rods 28, 29 and 30, respectively. The other ends of these rods are pivotally fastened to cranks 31, 32 and 33 respectively and are operated by them. The cranks 31, 32 and 33 are carried upon rotatable cross shafts 34, 35 and 36 respectively which also are provided with worm gears 37, 38 and 39 as shown in Fig. 3. These worm gears are driven respectively by corresponding worm gears 40, 41 and 42 which are carried by

55

60

70

80

85

90

95

100

the rotatable shaft 43. The shaft 43 is driven from any suitable source of power as through the grooved pulley 44 or other adequate method.

5 It is seen from Fig. 1 that as the gears 37, 38 and 39 are driven from the common shaft 43 and differ progressively in gear ratio; the gear 37 will rotate at the slowest speed, 38 at an intermediate speed and 39 at the highest speed. From the drawings it is also seen that the crank 31 has a greater throw than crank 32, which in turn has a greater throw than crank 33. Therefore as the shaft 43 is rotated the diaphragms 20 in the displacement mechanisms 16, 17 and 18 are oscillated back and forth in the cups 19 alternately compressing and expanding the air in them. From the relations as to stroke and speed before pointed out it is therefore seen that 20 the fluctuation in air pressure in the displacement mechanism 16 will resemble line 1 shown in Fig. 5; that the fluctuation in air pressure in displacement mechanism 18 will resemble line 3 in Fig. 6; and that the fluctuation in air pressure in displacement mechanism 17 will resemble line 5 shown in Fig. 7.

As previously explained, the bases of the displacement mechanisms are provided with 30 openings 22, 24 and 26 which register with corresponding ports 23, 25 and 27 respectively in the panel 11, and through which ports the displacement mechanisms are in working communication with the passage 12 in the interior of the panel. The panel 11 is also provided with control valves 46, 47 and 48. These valves are arranged to register with the respective ports 23, 25 and 27, being arranged on the panel on the other 40 side of the passage 12 in the panel so that as the valves are turned down or closed the several ports will be closed by the valve or one or more of the ports may be closed as one or another of the valves is turned down, thus cutting out the air-displacing mechanism which would otherwise operate through the cut-out port. Thus with valve 47 closed and the other valves open fluctuation approximately similar to 7 shown in Fig. 8 will be 50 produced while with all the valves open a fluctuation approximately similar to 9 shown in Fig. 9 will be produced provided the escape of imprisoned air in the air container or panel and its outlet communication is prevented 55 by the contact of the applicator 15 with the person.

Reference will now be made to the means of controlling the air pressure or vacuum utilized by the apparatus:

60 If no air is allowed to escape from the apparatus and the applicator is held in contact with the body with all the displacement mechanisms 16, 17 and 18 in operation, the imprisoned air will approximate line 9, Fig. 9, in its fluctuation with its average pressure

indicated by line 50 which represents approximately atmospheric pressure. In a similar way if mechanisms 16 and 18 only are in use, and no air is allowed to escape, the average pressure in the device is indicated by line 51 in Fig. 8 which represents approximately atmospheric pressure with fluctuations part of the time above and part of the time below it.

70 In order to produce a vacuum an inwardly-closing valvular device is provided. The valve 48 previously referred to is made tubular in form and carries on its outer end rigid arms 52 to which is attached by suitable means a flat strip of rubber 53 which in its normal position closes the outer end of the central passage 54 through the body of the valve. Whenever the pressure of the air in central passage 54 is greater than that of the air outside, the rubber strip 53 will be pushed away from the end of the tubular member, allowing air to pass outward, while entrance of air from the outside is prevented by the closing of the tube end by the rubber 80 whenever the pressure of the outside air exceeds that inside the machine.

85 If the machine, with the outwardly-operating check functioning, be operated slowly, air during the high pressure phase inside the machine will exceed in pressure that of the outside air and some air will pass out through the check valve, reducing the quantity of air in the machine and making the average air pressure lower than that of the atmosphere. This condition would be approximately represented by the line 9 in Fig. 9 with the atmospheric pressure represented by the line 55, or in case mechanisms 16 and 18 only were in use, by the line 7 in Fig. 8 with the atmospheric pressure represented by the line 56. It will be noted in the slow operation of the machine cited, the maximum pressure inside the machine will exceed atmospheric pressure by only the amount necessary to permit the flow of air outward through the check and which by proper adjustment of the check may be very slight indeed.

90 If now the machine be operated at its normal speed, one at which the diaphragm of mechanism 18 vibrates hundreds of times per minute, the air discharged from mechanism 18 passes through the port 27 at a very high velocity, and impinges directly into the tubular body of valve 48. As the inertia of the air column is quite high, at the velocity at which this air jet is moving, a considerable pressure will be built up against the rubber strip 53 allowing an escape of air even though the pressure of the air in chamber 12 at its maximum is much below that of the outside air. The intensity of the vacuum maintained in the machine is therefore to a certain extent independent of the ratio of displacement volume to total volume in-

closed, but is also a function of air velocity and inertia. The valve 48 being threaded on its exterior is adjustable as to the port 27 and may be moved closer to or farther away from the influence of the air jet passing therethrough, accordingly varying to a certain extent the intensity of the vacuum produced.

It will therefore be seen that with the inwardly-closing valve in full operation, with the machine running at full speed, the fluctuations of the inclosed air will approximate line 9 in Fig. 9 with reference to line 10 representing atmospheric pressure when all the mechanisms 16, 17 and 18 are operating, a fairly strong vacuum being maintained at all times in the interior air system of the machine. In case 16 and 18 only were in use then the fluctuations of the enclosed air will approximate line 7 in Fig. 8 with reference to line 8 representing atmospheric pressure.

For certain treatments it is desirable to use a less degree of vacuum than will be produced with the inwardly-closing valve located so near the high speed mechanism 18. In such cases the valve 48 is unscrewed from the panel and the hole in the latter closed by a solid plug having corresponding thread and a valve 57 controlling an auxiliary passage 58 is opened. Connected with the passage 58 by a threaded connection is a supplementary inwardly-closing valve 59 identical in operation with valve 48. The valve 59 is provided with a central passage 60 through it with orifice 61 leading to the atmosphere. This orifice is covered by a strip of rubber 62 and the rubber strip is held in position by a suitable retaining band 63 surrounding the body of the valve. Inasmuch as the valve 59 is located at a greater distance from and somewhat out of the influence of the high speed displacer 18, the average vacuum resulting from its use will be of less intensity, and it may be further regulated by manipulation of the shut-off valve 57.

Having shown how the vacuum is maintained and regulated in the air system within the machine, the means of conveniently regulating the amplitude of the fluctuations in the air pressure will now be considered:

The amplitude of the variations in air pressure within the apparatus is a function of the ratio of displacement volume to the total volume of the inclosed air system, and it may be altered by changing either one of these factors. As changing the displacement volume would involve changing the throw of cranks 31, 32 and 33, which would be inconvenient, I prefer to change the effective volume of the air system. I therefore provide cylindrical supplementary air chambers 65, 66 and 67 cast into the base of the machine. Connected with these chambers are conducting tubes 68, 69 and 70 which connect respectively by way of ports 71, 72 and 73 with the

chamber or passage 12 in the air container or panel. The ports 71, 72 and 73 are controlled respectively by valves 74, 75 and 76 in the panel. Thus it is conveniently possible by manipulation of the valves 74, 75 or 76 to throw any one or all of the supplementary chambers 65, 66 and 67 into communication with the passage 12 and thus add their volume to that of the rest of the inclosed air system. If greater amplitude of air fluctuation is desired, valves 74, 75 and 76 are closed and if less air fluctuation is desired one or more of the valves 74, 75 or 76 are opened cutting in one or more of the supplementary air chambers.

If, as will later appear, it is desirable to have the air fluctuations take place at a pressure higher than that of the atmosphere, the apparatus may be so adjusted as to bring about that effect. To that end there is provided an inlet check valve 80 the interior construction of which is shown in Fig. 4. This check valve is similar in principle to the other two mentioned. In it 81 is the controllable orifice leading from the atmosphere through the valve and by way of a passage 82 to connect with the passage 12. The passage 82 is controlled by a valve 83. The orifice 81 is covered by a strip of flat rubber 84 held in place by a flat spring 85 which bears against the ends of the rubber strip holding it in position, also, pressing at its mid portion against the opposite inside wall of the valve body at the point 86. Leading to the orifice 81 is an attached tube 87. With this arrangement of parts the rubber strip 84 will open the orifice 81 whenever the pressure in the attached tube 87 exceeds the pressure of the interior air and the valve 83 controlling the passage between the valve 80 and passage 12 remains open. To arrange for this higher pressure fluctuation valve 48 is removed from the machine and the orifice in which it is contained closed by a solid plug; valve 57 is closed and valve 83 is opened, and when the machine is operated under these conditions, air or medicated vapor drawn in through tube 87 is delivered to the applicator tube 13 under a fluctuating pressure higher than that of the atmosphere as for example the line 9 in Fig. 9 in which the line 88 represents atmospheric pressure.

Under certain conditions it is also desirable to deliver medicated vapors from an external source which is itself under pressure in a pulsating manner to the delivery tube. For this purpose I provide a plain tubular inlet 89 leading from an intake tube 90 to the passage 12, and controlled by the valve 91. Medicated vapor may be introduced from any source under pressure through the tube 90 which will then be delivered through the passage 12 and the delivery tube 13 in rapid pulsations as desired.

As previously stated, the applicator or de-

livery tube end 14 is shown fitted with an applicator 15 suited for use in the external ear. This applicator is of special design as it is important for the comfort of the patient that the applicator fit perfectly in the ear and itself be free from vibration. The end portion 92 of the applicator extended by a skirt 93 is approximately cone-shaped so that when placed in the ear the sides of the cone will effectively contact with the inner surface of the ear opening or meatus regardless of its size. Adjoining the base of the cone 82 is another oppositely-formed conical portion 94, adjoining which is a smaller sized and relatively thick walled neck section 95. The device is constructed of soft rubber or other elastic material. In using it the conical portion 92 is introduced into the ear opening as far as it will enter; added pressure will then distort both the conical surfaces 92 and 94, tending to flatten the cones and increasing the diameter of the device, thus making a very close fit in the ear opening regardless of its shape or size.

25 In the treatment of the ear, as before intimated, the applicator shown is first firmly inserted into the external ear opening. If the ear drum is badly depressed the machine is operated with a moderate vacuum, using the valve or check 48, the machine being adjusted, in other words, as shown in Fig. 1. The partial vacuum thus obtained will draw the ear drum into its normal position whereby it will be vibrated and thereby accustomed 30 to a correct position. If the depression of the ear drum is not so serious a less degree of vacuum may be employed, using in place of the valve 48 the valve or check 59. The middle ear may also be treated and the ear 35 drum vibrated from the inside by attaching a eustachian catheter to the end of the applicator tube 13. Pressure is applied for moving the ear drum into a correct position to which end the valve 48 is removed and replaced by a solid plug and the valve 57 closed. Medicated vapor is then introduced into the machine through the pipe 86 by way of the inlet check valve 80 if the medicated vapor be supplied at atmospheric pressure, or, if it be supplied under heavier pressure then it may be supplied directly into the machine by way of the intake tube 90.

40 For treatment of the scalp a heavy vacuum is desirable and the valve 48 may be used with a heavy elastic cap; for skin treatment a less degree of vacuum is desirable and the inlet check 59 may be employed in place of the check 48. For spinal massage a vacuum cup 45 may be used having some elasticity in its walls and the machine used with the supplementary chambers 65, 66 and 67 and, if desired, displacement mechanisms 16 and 17 cut off giving a very powerful single phase massage with intense vacuum of the combined intertissue and mechanical types.

If the machine is to be subjected to such hard continuous usage as to make the replacement of diaphragms 20 burdensome there may be substituted for them in the displacement mechanisms 16, 17 and 18 cylinders 96 as shown in Fig. 2 to which the several connecting rods 28, 29 and 30 are respectively pivotally secured.

Inasmuch as this system of intertissue and external mechanical pneumatic massage may be used by means of machines of widely differing designs, I do not limit myself to the particular design shown for producing periodic or rhythmic compound pneumatic fluctuations and for producing pressure fluctuations the average of which differs from that of the atmospheric pressure.

Having thus fully described my invention, I claim and desire to secure by Letters Patent of the United States:—

1. A vibratory apparatus comprising an air container having an air conductor leading therefrom with applicator carried by it, a plurality of air displacing mechanisms connecting with said air container for producing on operating said mechanisms mass vibrations of the air of different frequencies in said air container and air conductor therefrom, a vacuum-forming mechanism for producing on operating said mechanism a partial vacuum in said container, all of which mechanisms co-operating with one another whereby mass vibrations of the air produced by the operation of said air displacing mechanisms will be superposed on one another and the average thereof will be below atmospheric pressure, means for operating said mechanisms, a supplemental air chamber in communication with the interior of said air container, and means whereby said supplemental air chamber may be cut in or out.

2. A vibratory apparatus comprising an air container having an air conductor leading therefrom with applicator carried by it, a vibratory air displacing mechanism for effecting mass vibrations of the air within said air container and air conductor therefrom, an inwardly-closing valve arranged to prevent admission of air into the air container but permitting of the escape of air therefrom when the air within the air container is subjected by the displacing mechanism to such rapid mass vibration that the air due to its inertia will act to open the valve, and means whereby the air displacing mechanism may be vibrated with such rapidity that the valve will be opened by the air as aforesaid.

3. A vibratory apparatus comprising an air container having an air conductor leading therefrom with applicator carried by it, a vibratory air displacing mechanism for effecting mass vibrations of the air within the air container and air conductor therefrom, an inwardly-closing valve arranged to prevent admission of air into the air container,

but opening to permit escape of air from the air container when subjected to air pressure therein above atmospheric pressure, means whereby during the vibration of the air displacing mechanism a compression of air above atmospheric pressure will be obtained in a zone adjacent the air displacing mechanism, said valve being located within said zone, and means for vibrating the air displacing mechanisms.

4. A vibratory apparatus comprising an air container having an air conductor leading therefrom with applicator carried by it, a vibratory air-displacing mechanism for effecting mass vibration of the air within said air container and air conductor therefrom, and means whereby a partial vacuum may be obtained within said container and conductor therefrom by the operation of said air-displacing mechanism.
